HARVEY HARTER, OF PATERSON, NEW JERSEY, ASSIGNOR, BY MESNE ASSIGNMENTS, OF FORTY-NINE ONE-HUNDREDTHS TO JOHN McGOWAN, OF CAMDEN, NEW JERSEY

INTERMITTENT GRIP DEVICE FOR COPYHOLDERS

Application filed August 18, 1926. Serial No. 130,020.

This invention relates to copy holders and has for its object the provision of a novel device designed to stand upon a desk, table or the like and so constructed and arranged as to hold copy which may be exposed a line at a time to the view of the operator of a typewriter, adding machine or the like, the device embodying means intended to be located adjacent the keyboard of the machine and 5 deppressible to move the copy step by step for bringing the successive lines into view.

An important object of the invention is to provide a device of this character which is provided with an adjustment whereby the 15 control platen may be caused to move through a greater or less arc for displaying or bringing the successive lines into view, depending upon whether the copy is written in single, double or triple space.

20 A further object is to provide a device of this character which will permit the operator to keep his or her eyes on the copy without strain or difficulty of any kind owing to the fact that the device may be mounted directly 25 back of the a typewriter or at either side thereof, if preferred, the key being located in such position with respect to the typewriter or adding machine that the copy holder may be operated to bring an additional 30 al line into view without it being necessary for the operator to actually look at the key, the action of operating the shifting means for the holder being an extremely simple and easy one which will shortly become almost 35 automatic.

A still further object is to provide a readily operable manual adjusting device for moving the copy the slight distance required in case the copy be of a printed rather than typewritten 40 character, this same feature being of advantage in permitting readjustment of the copy to bring the lines thereon in proper relation to the guide or indicator.

An additional object is to provide a device of this character which will be simple and inexpensive in manufacture, easy to use and operate, positive in action, efficient and durable in service, and a general improvement in the art.

50 With the above and other objects and ad-

vantages in view, the invention consists in the details of construction and arrangement of parts to be hereinafter more fully described and claimed, and illustrated in the accompanying drawings in which:

Figure 1 is a side elevation of the complete device with a note book holder attached.

Fig. 2 is a side elevation of the intermittent grip device with the platen shaft in section.

Fig. 3 is a cross section along a line beyond that of Fig. 2.

Referring more particularly to the drawings, I have shown the device as comprising a main frame indicated broadly by the numeral 1, this frame being capable of manufacture as a single casting or as several pieces secured together. This frame includes upright or side members 2 terminating at their lower ends in horizontal portions 3 having supporting feet 4 thereon preferably padded as by being shod with rubber blocks or the like 5. The members 2 are connected by a transverse portion which may be integral therewith, or not, as preferred. At the outer 65 sides of the members 2 are spaced socket or bearing elements 7 arranged in pairs and with either pair of which may be connected the note book holding means.

The note book holder comprises a preferably rectangular frame 8 of light construction and consisting of any suitable or necessary number of pieces and including a transverse element 9 at the rear of which is a bearing 10 for a spindle or rod element 11 carried by a lazy tongs 12 which is connected at its rear end with a head member 13 engageable with a selected pair of the sockets or bearing members 7.

Journaled through the upper ends of the members 2 is a shaft 14 carrying a platen or large roller 15 covered with rubber or other similar material indicated at 16. The upper ends of the members 2 are shown as formed with recesses 17 and 18, the former being for the accommodation of the shaft 14 and the latter being for the accomodation of a shaft 19 which carries a rubber covered roller 20 coacting with the platen or roller 15. These two rollers act upon the copy paper and it is 100

clear that when either roller is rotated in the proper direction the copy paper will be moved either upwardly or downwardly, as the case may be. The recesses 18 are elongated so that the shaft 19 may move toward or from the platen or roller 15 so as to insure gripping the copy paper. Springs 21 are mounted on the members 2 and bear against the shaft 19 for urging the roller 20 into close relation to the platen. It should be mentioned that the recesses 17 and 18 are covered or closed by means of plates 22 bolted or otherwise secured upon the upper ends of the members 2, these plates being formed with outwardly projecting lugs 23 for a purpose to be described.

Suitably secured to the upper ends of the members 2 is a paper guide 24 which may actually be formed of sheet metal and which may therefore be of a hollow formation with the ends provided with attaching plates 25 from which project laterally extending inclined lugs 26 for a purpose to be described. The member 24 extends above the platen 15 and the plate members 25 at the ends thereof are formed with ears 27 which are apertured to form bearings for a U-shaped frame member 28 which is pivoted thereto and which carries rollers 29 coating with the platen 30 for holding the upper end of the copy paper and preventing it from falling forwardly over the exposed copy, thereby preventing obstruction of the operator's view. The weight of this member 28 and the rollers thereon 35 should suffice to hold the paper down without it being necessary to provide springs, though if springs are preferable I reserve the right to employ them. The above described lugs 26 constitute stops against which the arms of the member 28 rest when this member is swung upwardly and forwardly.

The numeral 30 designates the forward guide or line indicator which may be formed from a single piece of sheet metal and which 45 is provided at its ends with wings or ears apertured for the passage of the shaft 19 and formed with laterally extending lugs 33 which rest upon the tops of the members 22. Of course, the copy paper in addition to passing between the platen 15 and roller 20 must 50 pass between the guides 24 and 30 as indicated by short dash lines in Figure 2.

At one side of the machine the shaft 14 carries a ratchet 34, a few of the teeth of which 55 are exposed through an opening 35 in a drum or shell 36 which is rotatably mounted upon the shaft 14 and which is provided with a handle 37 whereby it may be shifted to a limited extent for bringing a selected one of a plurality of notches 38 into engagement with the laterally extended end 39 of a keeper spring 40 mounted on the frame 2. At the ends of the series of notches 38 are stop lugs 41 which will limit rotary adjustment of the shell 36 in both directions. Obviously, the

position of the opening 35 will determine the degree of movement of the ratchet and consequently the platen when the ratchet is engaged by an operating pawl 42 which is pivoted at 43 upon an arm 44 rotatably mounted on the shaft 14. A spring 45 is connected with the arm and pawl for normally holding the latter in operative relation to the shell, the opening therein, and the ratchet teeth exposed at the opening.

The control means or operating means for the device comprises an elongated lever 46 pivoted intermediate its ends at 47 on one of the frame members 2 and terminating at its forward end in a key 48 located within convenient reach of the operator so as to be readily depressed whenever it is necessary to bring another line of copy into view above the guide or indicator 30. At its rear end the lever 46 is pivotally connected at 49 with the lower end of a vertically slidably mounted rod 50 which has its upper end pivotally connected with the arm 44 and pawl 42 at the point 43. The lever 46 is normally maintained in potential position by a coil spring 51 which abuts against a collar 52 on the rod 50 and against a rigid abutment 53 on one frame member 2.

Secured upon one end of the shaft 19 is a segmental gear 54 with which meshes a segmental gear 55 having an elongated handle 56 thereon, the purpose being that by grasping the handle 56 and thereby turning the gear 55 the gear 54 will be correspondingly turned for rotating the roller 20 to a limited extent so that the copy paper may be moved to a very slight extent if desired or to a slightly greater extent than is effected by actuation by means of the key, it being consequently possible to readjust in case of non-alinement 100 of the copy with the guide 30. It should also be mentioned that one end of the shaft 14 carries a knob by means of which the platen may be freely turned for feeding the copy when it is first inserted and before the line 105 mechanism is brought into play.

In the operation of the device, the copy is inserted from underneath between the platen 15 and roller 20 and the handle or knob is turned to bring the copy upwardly between the guides 30 and 24 into such position that the topmost line will be exposed above the former. It is of course understood that the shell 36 must be shifted, by means of the lever 37 to bring the opening 35 at the proper position with respect to the pawl 42, this adjustment depending upon whether the copy is in single, double or triple space. If the ratchet teeth do not match up with the lines of the copy readjustment may be made by moving 120 the lever or handle 56 so that the roller 20 will move the copy independently of movement of the platen. The operator then copies the line exposed or does what other manipulations are necessary, and upon conclusion 125 130

of the copying of the line it is intended that the key 48 be depressed whereupon the rod 50 will move upwardly and cause the pawl 42 to engage the ratchet teeth and rotate the platen to a sufficient extent that the next line of copy will be brought into view above the guide or indicator 30. The key 48 is depressed at the end of every line until the entire copy has been moved between the platen and roller. The various details of adjustment and the like have already been explained and it is believed that a repetition thereof will be unnecessary. It is thought that the construction, operation and advantages will be readily apparent to one skilled in the art without further explanation.

While I have shown and described the preferred embodiment of the invention, it should be understood that I reserve the right to make such changes in the form, construction and arrangement of parts as will not depart from the spirit of the invention or the scope of the subjoined claims.

Having thus described the invention, I claim:

1. In an apparatus of the character described a ratchet, a shell rotatably mounted and surrounding the ratchet, said shell having an opening exposing a plurality of the ratchet teeth, a lever operated rod, a pawl carried thereby cooperating with said exposed teeth, the shell being adjustable to vary the relation of the opening therein to the initial position of the pawl, and a retaining member, the shell having a series of notches selectively engageable by the retaining member.

2. In an apparatus of the character described, a ratchet, a shell rotatably mounted and surrounding the ratchet, said shell having an opening exposing a plurality of the ratchet teeth, a lever operated rod, a pawl carried thereby cooperating with said exposed teeth, and means for holding the shell in selected position comprising a spring bearing against the periphery thereof, the shell being provided at its periphery with a series of notches engageable by said spring.

HARVEY HARTER.
